UNITED STATES PATENT OFFICE.

KELSO MURDOCK, OF CINCINNATI, OHIO, ASSIGNOR TO THE MURDOCK MANUFACTURING AND SUPPLY COMPANY, OF CINCINNATI, OHIO, A CORPORATION OF OHIO.

REGULATOR FOR ANTIFREEZING DRINKING FOUNTAINS.

1,419,292.

Specification of Letters Patent. Patented June 13, 1922.

Application filed March 5, 1920. Serial No. 363,618.

To all whom it may concern:

Be it known that I, KELSO MURDOCK, a citizen of the United States of America, and a resident of Cincinnati, in the county of 5 Hamilton and State of Ohio, have invented a new and useful Improvement in Regulators for Antifreezing Drinking Fountains, of which the following is a specification.

My invention relates to drinking fountains 10 of the type covered by United States Patent No. 1,146,946. The objection to the regulating means of the fountain referred to is that when the device is installed there is nothing to prevent the plumber from crushing 15 the ball valve H' employed in such fountains as he turns the pipe G in his efforts to regulate the flow. Also there is nothing to prevent the supply pipe G becoming disengaged from the bonnet h, resulting 20 in dislocation of the parts of the regulating device.

The object of my invention is to provide a regulator that can be properly adjusted before installation of the drinking fountain 25 and that can be subsequently regulated as desired without any danger of smashing the ball valve employed in such fountains.

Another object is to provide means that will prevent dislocation of the regulator 30 parts.

These and other objects are attained by the means described hereinafter and disclosed by the following drawing, in which:—

Fig. 1, is a vertical section of a drinking 35 fountain with my invention applied to it.

Fig. 2, is a sectional view of the bonnet on an enlarged scale, forming a detail of my invention.

Fig. 3, is a view on line 3—3 of Fig. 2. 40 A supply pipe B is attached to a key A. A regulator D is adapted to reciprocate in a way a, formed in the key A. An adjustable neck d' on the regulator extends through the base of bonnet E and is there engaged 45 by a valve F. The flow passes from the recess e in which the valve F is located, through a central bore in the regulator to the way in the key and then through the supply pipe. The flow is modified by extending the neck into or withdrawing it 50 from the recess e to greater or less distances.

The key A is attached to the lower end of the supply pipe B and is encased within the chamber e³ of the bonnet E through the 55 upper end of which the supply pipe extends. The lower end a of the key is open. The

key A has a way a', preferably of a square oblong shape, formed in it. This way communicates with the bore of the supply pipe.

The regulator D has a block d, of a shape 60 similar to, but slightly smaller than the way a', adapted to reciprocate in a'. The block d is so formed or of such size that it cannot enter the supply pipe.

The block is seated in the way a' and extends from the lower end a. The collar d⁵ formed on the regulator limits the distance to which the regulator may enter way a'. Beyond the collar d⁵ and exterior to the key is a threaded neck d' formed on the regulator. 70 At the end d³ of the threaded neck d' is a series of notches d² extending diametrically across the regulator. These notches extend for a short distance along the threaded section of the regulator. A central 75 bore d⁴ extends longitudinally through the regulator, and communicates with the supply pipe and recess e, formed on the under side of base e⁴, of bonnet E. The threaded neck d' engages in threaded passage e' extending 80 through base e⁴.

The notches d² connect with bore d⁴. The recess e is formed in the bonnet E. When the regulator D is screwed through the base e⁴, the lower end of the regulator enters the 85 recess e. A ball valve F is located in the recess and seats upon the surface d³ of the regulator under certain conditions. The bonnet and supply pipe are enclosed within a drinking fountain casing C having a bubbler b at the upper end of the supply pipe B. A foot lever G actuates the spring operated casing H to which is attached a valve operating device K. A valve M is utilized to open and close the supply nozzle N 90 through the operation of the foot lever G and the valve operating device K. The operation of the valve operating device K and of the valve M are the same as explained in Patent 1,146,946. 95

The operation of the device is as follows:—

When the foot lever G is depressed the valve M is lifted from the supply nozzle N allowing a flow of water to pass through the 105 regulator to the supply pipe and to the bubbler b. Before the water reaches the regulator, the ball valve F is lifted and seats upon the under surface d³ of the regulator D closing the lower end of the bore d⁴. The 110 water passes around the valve F, through the notches d² into the bore d⁴ and then

through the supply pipe to the bubbler. When the pressure is removed from the lever G the valve M is seated upon the supply nozzle N by the action of spring P. The water 5 in the supply pipe and regulator and in the chamber about the valve M drains from these sections in a manner well known, and as explained in Patent 1,146,946. The downward rush of the water in the supply pipe B forces 10 the ball valve F from its seat upon the surface d^3 , speedily draining the supply pipe. The flow of water is modified by screwing the regulator D through the bonnet E so as to expose a greater or lesser portion of the 15 notches d^2 interiorly to the recess e. If the flow is to be increased the regulator is screwed so as to extend the notches to a point further within the recess; if the flow is to be decreased, the regulator is screwed 20 to raise the notches above the recess and in contact with the threaded sides of the bonnet E. The collar d^5 limits the extent to which the section d' of the regulator can be injected into the recess e making it impossible 25 to smash the ball valve F. This collar also sets upon the ends a of the key A and prevents the dislocating of the parts. The regulator can be adjusted, after the fountain is installed, by turning the supply pipe B, 30 by revolving the bubbler b as explained in Patent 1,146,946. The bubbler and supply pipe are ordinarily secured to one another, thereby forming a continuous guide duct or supply pipe for the water. The pipe B 35 transmits rotary movement to the regulator D by means of the key A. If the regulator should be moved in such direction as would tend to separate it from the bonnet, the shoulder d^5 contacting with the lower end a 40 of the key will prevent such dislocation. If the regulator is turned in the opposite direction, the collar d^5 contacting the shoulder e^2 on the bonnet will prevent the neck d' from crushing the ball valve F. 45 Having thus described my invention, what I claim is:—

1. In a regulating device for a hydrant the combination with a bonnet having a base with a walled passage terminating in a recess, of an adjustment device comprising a regulator having a central bore and comprising a neck adjustably extending through the passage and having series of notches in the under surface thereof connecting with the central bore, to register with the recess and the passage, and a block, a key having a way connecting with the bore in the regulator and adapted to permit reciprocation of the block therein, a supply pipe attached 50 to and communicating with the way, and a valve located in the recess engaging the neck.
2. In a hydrant an adjustment device comprising a bonnet having a chamber, a recess, and a passage connecting the chamber

and recess, a regulator within the chamber, having a central bore and engaging adjustably in the passage, a valve located in the recess adapted to seat in the regulator bore and in the passage, means adapted to adjust 70 the regulator in the passage, and a supply pipe communicating at all times with the central bore.

3. In a hydrant an adjustment device comprising a bonnet having a chamber, a recess, and a passage connecting the chamber and the recess, a regulator within the chamber having a central bore, and comprising a block, a collar on the block and a neck extending beyond the collar, means in the passage for holding said block in adjusted positions, and a valve located in the recess adapted to seat in the regulator bore and in the passage, and a key adapted to engage 80 the block.

4. In a hydrant an adjustment device comprising a bonnet having a chamber, a recess, and a passage connecting the chamber and the recess, a regulator having a central bore communicating with the recess and comprising a block disposed within the chamber, a collar on the block, and a neck extending beyond the collar and engaging adjustably in the passage, a valve located within the recess adapted to seal the central 90 bore and in the passage, a key within the chamber, having a way adapted to permit reciprocation of the block therein and communicating with the central bore, and a supply pipe attached to the key and communicating with the way.

5. In a hydrant an adjustment device comprising a bonnet having a chamber, a recess, and a passage connecting the chamber and recess, a regulator within the chamber having a central bore and engaging adjustably in the passage, a valve adapted to seat in the regulator bore and in the passage, means adapted to adjust the regulator in the passage and means in the passage for holding 105 the regulator in various positions.

6. In a hydrant an adjustment device comprising a base having a passage therethrough, a regulator mounted in the passage and having a central bore and a series of notches in the under surface thereof, such notches extending outward from the central bore, means in the passage for holding said regulator in adjusted positions, a valve adapted to seat in the regulator bore adjacent the under surface of the regulator, means to adjust the regulator in the base whereby the protrusion of the under surface of the regulator from the passage may be varied, and means limiting the extent of such 115 adjustment of the regulator.

In witness whereof, I have hereunto subscribed my name this 2nd day of March, 1920.

KELSO MURDOCK.
